Primary Examiner — Sanjeev Paul(74) *Attorney, Agent, or Firm* — ScienBiziP, P.C.(57) **CLAIM**

The ornamental design for a blanket, as shown and described.

DESCRIPTION

FIG. 1 is a perspective view of a blanket, showing my new design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof.

FIG. 7 is a bottom plan view thereof; and,

FIG. 8 is an enlarged view of an area labeled 8 in FIG. 3. The broken lines in the drawings depict unclaimed portions of the blanket and boundaries and form no part of the claimed design.

1 Claim, 8 Drawing Sheets(56)
